CLAIM

We claim the ornamental design for a fishing downrigger
assembly, as shown and described.

DESCRIPTION

FIG. 1 is a perspective view of the fishing downrigger
assembly forming a part of the present design;
FIG. 2 is a right side view forming a part of the present
design;

FIG. 3 is a left side view forming a part of the present design;
FIG. 4 is a top view forming a part of the present design;
FIG. 5 is a bottom view forming a part of the present design;
FIG. 6 is a front view forming a part of the present design;
and,
FIG. 7 is a rear view forming a part of the present design.
